UNITED STATES PATENT OFFICE.

FRANK H. ELDRED AND CHARLES HUTCHINGS, OF MORRIS, ILLINOIS.

DESIGN FOR AN AUTOMOBILE RADIATOR ORNAMENT.

Application filed August 16, 1924. Serial No. 10,471. Term of patent 3½ years.

To all whom it may concern:

Be it known that we, FRANK H. ELDRED and CHARLES HUTCHINGS, citizens of the United States, residing at Morris, in the county of Grundy and State of Illinois, have invented a new, original, and ornamental Design for Automobile Radiator Ornament, of which the following is a specification, reference being had to the accompanying drawing, forming part of this specification.

The figure of the drawing is a perspective view of an automobile radiator ornament showing our new design.

We claim:

The ornamental design for an automobile radiator ornament as shown.

FRANK H. ELDRED.
CHAS. HUTCHINGS.
